UNITED STATES PATENT OFFICE.

EDWARD ANDERSON AND JOHN E. PARKS, OF CLEVELAND, OHIO.

DESIGN FOR A COMBINATION STATIONERY DEVICE.

48,881.

Specification for Design.

Patented Apr. 18, 1916.

Application filed January 29, 1916. Serial No. 75,180. Term of patent 14 years.

To all whom it may concern:

Be it known that we, EDWARD ANDERSON, a subject of the King of Sweden, and JOHN E. PARKS, a citizen of the United States, residing at Cleveland, in the county of Cuyahoga and State of Ohio, have invented a new, original, and ornamental Design for Combination Stationery Devices, of which the following is a specification, reference being had to the accompanying drawing, forming a part thereof.

The figure is a perspective view of a combination stationery device, showing our new design.

We claim:

The ornamental design for a combination stationery device, as shown.

EDWARD ANDERSON.
JOHN E. PARKS.

Witnesses:

L. J. FINK,
M. P. FRYE.
